UNITED STATES PATENT OFFICE.

JOSEPH PHELPS, OF NORTH CALDWELL, NEW JERSEY, ASSIGNOR TO REMINGTON TYPEWRITER COMPANY, OF ILION, NEW YORK, A CORPORATION OF NEW YORK.

TYPEWRITING MACHINE.

Application filed May 25, 1921. Serial No. 472,471.

To all whom it may concern:

Be it known that I, JOSEPH PHELPS, citizen of the United States, and resident of North Caldwell, in the county of Essex 5 and State of New Jersey, have invented certain new and useful Improvements in Type-writing Machines, of which the following is a specification.

My invention relates especially to paper 10 controlling mechanism for typewriting machines, and its main object is to provide improved mechanism of the character specified. More specifically stated the object of the invention is to improve the construction 15 disclosed in my prior Patent No. 1,100,442, granted June 16, 1914, by supplying additional controlling devices for one of the work sheets.

To the above and other ends, which will 20 hereinafter appear, my invention consists in the features of construction, combinations of devices, and arrangements of parts hereinafter described and particularly pointed out in the claims.

25 In the accompanying drawings,

Figure 1 is an end view, with certain parts in section of the upper part of a No. 11 Remington typewriting machine of the tax billing style embodying my invention.

30 Figure 2 is a fragmentary perspective view showing the feed or pressure rolls for the controlling devices, including the novel devices with which my invention is more particularly concerned, the paper deflector 35 being shown swung up for the sake of clearness.

Figure 3 is an operating view corresponding to Fig. 1 but omitting some of the parts shown in said figure and showing other 40 parts in different relationships.

Figure 4 is a fragmentary horizontal sectional view taken on the plane indicated by the dotted line 1—1 in Figure 1 and looking downward.

45 Figure 5 is an enlarged transverse sectional view taken on a plane indicated by the dotted line 2—2 in Figure 2 and looking in the direction of the arrow at said line.

Figure 6 is a fragmentary sectional view 50 on an enlarged scale, said view being taken on a plane indicated by the dotted line 3—3 in Figure 1 and looking in the direction of the arrow.

Figure 7 shows a modification.

55 The main frame of the machine (Fig. 1)

comprises posts 1 supporting a top plate 2 that has a depression 3. Grooved guide-ways 4 and 5 co-operate through rollers 6 with the front bar 7 and rear bar 8 of a carriage truck which also includes end bars 9. Said truck supports a platen frame or carrier comprising two end bars 10 and a connecting cross bar or bridge piece comprising a vertical portion 16 and a horizontal portion 17, only the left-hand one of the two end bars 10 being shown in the drawing. The platen frame is rigidly secured to the truck as shown in my aforesaid patent. Lugs or uprights 19, integral with and projecting upward from the part 17 provide supports for the pressure rollers hereinafter described. A rotary platen 20 having an axle 21 is mounted on the carriage frame and the types (not shown) are adapted to co-operate with the front face of said platen. 75 A paper table 23 arranged behind the platen has ears 24 bearing on a rod 25 secured to an extension 10^a on the end plate 10 and the corresponding extension (not shown) on the right-hand end plate. Braces 26 are screwed 80 to the arms 28 that support the usual column stop bar 29 carrying column stops 30 with which co-operate denominational stops 32. Slidably mounted on the paper table is an end stop device 36 provided with an end stop proper 36^a. The paper table is also provided with a side guide or gage 39. Curving round the under side of the platen is a paper apron or deflector 40 that terminates below the printing line at the front of 90 the platen, said deflector being screwed to ears 42 that bear loosely on a sleeve or hollow rock shaft 43 extending lengthwise of the platen and bearing rotatably in the uprights 19. The ends of the sleeve 43 are 95 cut away, as indicated at 44, to co-operate with shoulders 45 on collars 46 screwed to a rock shaft 48 arranged within the sleeve or hollow shaft 43 and having projecting ends which bear in the end bars of the 100 platen frame. Pairs of angular arms 49 bear loosely on the sleeve 43, each pair carrying a rod 51 that supports the sections 52 of a main feed roller. Drawsprings 53 anchored to the bridge piece are connected to 105 the arms 49 and maintain the main feed roller sections normally engaged with the platen, said sections protruding through openings 52^a in the deflector 40. Outside the uprights 19 are arranged carriers each 110

comprising arms 56 and a cross bar 57, said carriers supporting marginal or terminal feed or pressure rollers 58. The inner arm of each carrier bears on the sleeve 43 and the outer arm on the rod 48. Drawsprings 59, anchored to the bridge piece, constantly press said terminal rollers towards the platen with which they are adapted to engage through openings 58^a in the deflector 40. Crank arms 61 fixed to the sleeve or hollow rock shaft 43 are provided with studs 63 which overlie the associate arms 49. When the shaft 43 is rocked it will operate through the crank arm 61 and stud 63 to swing the arms 49 downward and overcome the springs 53, releasing the main feed roller throughout its length, this movement being independent of the terminal rollers 58 and being accomplished by devices comprising a plate-like arm 65 which is secured to the sleeve 43 and is adapted to co-operate with a wheel or rotary cam 69 having a pivot 70 adjustably mounted in the bottom of the depression 3. During the traveling movements of the platen carriage the arm 65 will engage with the cam 69, the cam operating to force the arm rearward, rocking the sleeve 43 and automatically releasing the main feed roller during the carriage travel. At the same time the loosely mounted deflector, which is normally maintained in spring pressed engagement with the platen as hereinafter described, will be freed and will drop down at its forward portion away from the platen, providing an opening or passageway for the paper introduced at the front. The terminal rollers 58 are releasable at will by devices comprising crank arms 76 fixed to the shaft 48 and having studs 78 overlying the outer arms 56 and adapted to swing said arms on the shaft 48 to overcome the springs 59 and release the rollers 58. The shaft 48 may be rocked as described by devices comprising a crank arm 79 secured to one end of the shaft and connected to a link or strap 81 enlarged at its upper end and receiving a boss 82 integral with an arm 83 pivoted eccentrically of the boss 82, said crank arm terminating in a finger piece or key 85. By pushing the key 85 rearward the strap 81 is pressed downward, depressing the crank arm 79 and rocking the shaft 48 to release the terminal rollers 58. This movement of the shaft 48 operates through the shouldered collars 46 to rock the shaft 43 and effect the release of the main feed roller simultaneously with the marginal rollers. The shaft 48 as it turns forward brings the shoulder 45 at the forward side of each collar into engagement with the corresponding cut-off or shoulder 44 on the shaft 43, thus forcing said shaft to turn with the shaft 48. Thus the main or intermediate feed or pressure roller is released either automatically or by hand,

the automatic release occurring independently of the terminal rollers while the manual release on the other hand is effected concurrently with that of the terminal rollers. A spring bail is provided to co-operate with the front upper side of the platen, said bail comprising side arms 86 and a cross rod 87 having pressure rolls 88. The arms 86 are secured to a rock shaft 89 which bears in brackets 90 fixed to the carriage truck. Drawsprings 91 exert pressure on the bail to maintain the rollers 88 contacting with the platen above the printing line. On the cross rod 87 is mounted a side guide or gage 92 which co-operates with the left-hand edge of a narrow sheet 94, the width of said sheet being less than the distance between the terminal rolls 58, the gage 92 being adjusted somewhat to the right of the left-hand roller 58. The rollers 58 co-operate with the side margins of a wide record sheet 95 which is introduced into the machine from the rear in the usual way, the side gage 92 co-operating with the left-hand edge of said record sheet to position it properly lengthwise of the platen. The record sheet is passed up at the front side of the platen together with the transfer or carbon sheet 96 and is controlled by the rolls 88 above the printing line. In order further to guide the narrow sheet 94 when introduced at the front, there is provided a guide rod or shaft 97 which bears in the side arms 86 and is arranged a short distance forward of the cross rod 87 providing a space between the two. The gage 92 is formed with a hole through which the guide rod 97 passes.

The mechanism thus far described, which is fully disclosed in my prior patent aforesaid, is especially adapted for use in tax billing work wherein the tax bills or narrow sheets usually comprise a plurality of folds with interleaved carbon sheets, thus making a comparatively thick packet, although for convenience of illustration a single thickness only is shown in the drawing. This thick packet is difficult to control properly, and in order to maintain it close to the platen, especially in the neighborhood of the printing line, I have found it desirable to provide additional controlling devices with which my present invention is more particularly concerned. Said additional devices comprise pressure rolls which are arranged along the platen at the front side thereof just below the printing line and are coupled up or so connected with the main roller 52 as to be automatically controlled by the devices which control said roller 52. My novel devices comprise ears 101 which are fixed to and project forward and upward from the front of the upright part 16 of the bridge-piece. These ears are perforated to provide bearings for a rock shaft 102 that is square in cross section. The left-hand end of this

rock shaft bears in an ear 17^a projecting from the left-hand end portion of the bridge-piece. In the present instance the rock shaft 102 terminates short of the right-hand end of the bridge-piece but this is a matter of detail and where desirable the rock shaft may extend the full length of the platen and the bridge-piece. Mounted on the rock shaft are a pair of roller carriers, each pair comprising two crank arms 103, provided with inwardly projecting hub portions 104, which fit over the rock shaft 102 and bear loosely thereon. Each pair of carrier arms 103 are confined between two of the ears 101 which prevent outward displacement of said arms in respect to each other. At their outer ends the carrier arms are perforated to provide bearings for pintles 105 and pressure rollers 106. These pressure rollers may be of metal and are forward or out of line with the main and terminal rollers which are in line with each other. Said rollers 106 are adapted to co-operate with the platen 20 at its front lower side below the printing line, protruding through narrow slots or openings 107 in the front portion of the deflector 40. The side edges of the deflector outside the openings 107 rest on the free ends of the carrier arms 103, the swinging deflector 40 being thus supported by the carriers. The pressure rollers 106 are constantly urged towards the platen by springs 108 that are coiled around the rock shaft 102. There is one of these springs arranged close to and inside of each of the hubs 104, one end of the spring bearing in a hole in the collar and the other end abutting against the front face of the part 16 of the bridge-piece. Collars 109 secured by set screws 110 to the rock shaft 102 prevent displacement of the springs in respect to the hubs 104 and also prevent undue movement of the carrier arms 103 of each pair towards each other. This feature of construction will be clearly understood from Fig. 6. From an inspection of Fig. 2 it will be noted that the supplemental pressure rollers 106 are arranged forward of and so to speak inside the marginal rolls 58 so that said rollers 106 are adapted to co-operate with the marginal or side portions of the narrow sheet 94 and not with the edge or marginal portions of the wider sheets 95 and 96.

It is desirable to release the pressure devices 106 automatically at the same time that the other pressure devices 52 for the narrow sheet are released, and to this end means are provided which comprise crank arms 111 provided with hubs 112 which fit over and are secured by set screws 113 to the rock shaft 102. One of these crank arms 111 is arranged outside of each ear 101 and in association with the carrier or crank arm 103 inside said ear. A lateral pin 114, fixed to the crank arm 111 and extending inward engages loosely in a hole in the associate arm 103 (Fig. 6). Fixed to the left-hand end of the rock shaft 102, just inside the ear 17^a, is a downwardly extending crank arm 115 (Figs. 1, 2 and 3), said crank arm having a collar 116 that receives a set screw 117 by which the crank arm is secured in place on the rock shaft. A notch or cut-away 118, formed in the upright portion 16 of the bridge-piece, provides room for the crank arm 115 and also for the forward portion of a horizontally arranged link 119 which is pivotally connected at 120 with the crank arm 115. The rear end portion of the link 119 is somewhat higher than the front portion, to which it is joined by a curved or offset part, and is pivotally connected at 121 with the free outer end of an upstanding crank arm 122 provided with a hub 123 which fits over a stub rock shaft 124 and is secured thereto by a set screw 125. The stub shaft is arranged at the rear of the bridge-piece and its left-hand end bears rotatably in an ear 17^b projecting rearward from the left-hand end of said bridge-piece. The right-hand end portion of the stub shaft 124 bears in the left-hand upright 19. A collar 126 fixed to the stub shaft at the left of said lug prevents end-wise displacement of said stub shaft towards the right, while the collar 123 contacts with the inner face of the ear 17^b to prevent displacement of said stub shaft towards the left, the stub shaft being free, however, to rock or rotate in its bearings. Rocking motion is communicated to the stub shaft from the hollow rock shaft or sleeve 43 by means of a crank arm 127 on the right-hand end portion of the stub shaft which projects beyond the lug 19. Said crank arm extends upward and its free end is formed with a slot 128 which is loosely engaged by a pin 129 that projects laterally rightward from the left-hand arm 49.

It will be understood that the supplemental pressure rollers 106 will be released when the key 85 is actuated to release the rollers 52 and 58, and that said rollers 106 will also be released when devices 65 and 69 operate during traveling movements of the carriage to release the rollers 52 independently of the terminal rollers 58. In the former instance this will result in the rocking of the shaft 48 acting through the shouldered collar 46 to rock the shaft 43 and to release the main rollers 58, as has been described, the pins 63, depressing the arms 49 to effect this result. Simultaneously the pin 129 on the left-hand arm 49 will act on the crank arm 127 to rock the shaft 124, swinging the crank arm 122 rearward, thus drawing rearward the link 119, swinging the crank arm 115 rearward and rocking the shaft 102. The movement of 130

said shaft 102 in turn will be transmitted through the crank arms 111 and pins 114 to the carrier arms 103, which will be swung forward, overcoming the springs 108 and 5 throwing the rollers 106 to the released position, and permitting the deflector 40 to drop down away from the platen into released position, thus providing a considerable mouth or pocket at its forward edge 10 to facilitate the front feeding of work sheets between the deflector and the platen. When the release key is restored the paper controlling devices will return under the action of their restoring springs to normal 15 position in respect to the platen. It will be understood that the springs 53 will, through the described train of connections, affect the pressure rollers 106 to some extent during this restoring operation.

20 On the other hand, when the plate-like arm 65 is acted on by the cam 69, the sleeve 43 will turn independently of the shaft 48, releasing the pressure rollers 52 without affecting the terminal rollers 58. During 25 this releasing operation the actuating pin 129 will operate as before through the train of connections comprising the crank arm 127, rock shaft 124, crank arm 122, link 119, crank arm 115, rock shaft 102 and 30 crank arms 111, to swing the carrier arms 103 and throw off the rollers 106 simultaneously with the rollers 52. The parts when in the released position just described are illustrated in Fig. 3. The restoration of 35 the parts to normal position will be effected automatically when the arm 65 is released from the control of the cam 69 by a suitable movement of the carriage.

The mechanism herein described is adapt- 40 ed for use with various forms or styles of commercial typewriting, although in its present form it was more particularly designed for the writing of tax bills and records thereof. In using it for such work 45 the operator first presses the release key 85 rearward, releasing all the feed rollers. The record sheet 95 and carbon sheet 96 are then introduced together at the rear of the machine over the paper table, properly positioned against the side guide 39, and are passed downwardly around and under the platen and over the deflector 40, being advanced above the printing line and introduced under the pressure bail. The release 50 key 85 is then returned to normal position, resulting in the return of all the pressure rollers into co-operative engagement with the platen. The carriage is then released from the escapement devices, as by a release key 55 60 or through a tabulating operation, and permitted to move towards the left, bringing the arm 65 into engagement with the cam 69, releasing the main feed roller 52, the supplemental pressure rollers 106 and the 65 deflector 40, but independently of the ter-

70 minal rollers 58 which are not affected. Preferably the automatic releasing devices 65 and 69 are so adjusted as to effect the release of the main and supplemental rollers only after the end of the printing line has been reached. With these rollers and the deflector thus released the operator inserts the narrow sheet or sheets 94 from the front of the machine, guiding said sheet or sheets against the gage 92. Said sheets are front 75 fed over the guide rod 97 and forward of the rolls 88, and thence downward between the platen and the supplemental rollers 106, being slid rearward over the deflector 40 and passing between the main feed 80 roller 52 and the platen, the side edges of said sheet or sheets of course clearing the terminal rollers. The end of the sheet or sheets will be arrested against the end stop 85 36°. The operator then restores the carriage from left to right, the main and supplemental feed rollers and the deflector engaging with the sheet or sheets 94, which will thus be controlled in superposed relationship with the record sheet and in position to receive the line of writing. Assuming that as usual each narrow sheet or tax 90 bill 94 receives but a single line, the carriage will be released when the end of this line has been written, causing the arm 65 to 95 co-operate with the cam 69, thus releasing the written sheet or sheets 94, which may then be removed and substituted by another sheet which will undergo the manipulations hereinbefore described. In restoring 100 the carriage from left to right the usual line spacing handle will be operated, first to space the record sheet prior to the restoration of the main feed roller into engagement with the platen so that the line 105 spacing operation does not affect the newly adjusted narrow sheet but only the underlying wide record sheet. This underlying sheet of course receives the type impressions through the carbon paper 96, simultaneously 110 with the writing of the narrow sheet.

As has been stated, the tax bills usually comprise a plurality of folds with interleaved carbons, making a thick packet and my present improvement has been found 115 in practice greatly to facilitate the control of the printing portion of such a packet maintaining the portion of this packet opposite the printing line in proper condition to receive the full and clear imprints of 120 the types. Only minor changes are necessary to adapt the present form of my improvements for use in connection with the mechanism disclosed in my aforesaid prior Patent No. 1,100,442.

125 Various changes may be made without departing from my invention. For example, it may be found necessary positively to connect the pressure rolls 106 with the platen 20 to insure proper feeding of the paper. 130

This may be accomplished as illustrated in Fig. 7 by mounting the pressure rollers 106 on a common shaft 130 and fixing to this shaft at its left-hand end a small toothed wheel or pinion 131 which constantly intermeshes with a toothed wheel 132 which is fixed to the left-hand end of the platen axle 21. The shaft 130 may be supported near its outer ends by additional hanger arms 133. By this construction the pressure rolls will always be caused to turn by rotary movements communicated to the platen.

What I claim as new and desire to secure by Letters Patent, is,

1. In a typewriting machine, the combination of a traveling platen, a releasable paper feed roller mounted on a sleeve, a second paper feed roller in line with said first roller and mounted on a shaft, a third feed roller mounted on another shaft and arranged forward of the first two feed rollers, an arm on said sleeve, means for automatically actuating said arm during the travel of the platen, connections between both of said shafts and said sleeve, and means operative by hand to release said second and third feed rollers.

2. In a typewriting machine, the combination of a traveling platen, a releasable paper feed roller mounted on a sleeve, a second paper feed roller in line with said first roller mounted on a shaft, a third feed roller mounted on another shaft and arranged forward of the first two feed rollers, an arm on said sleeve, means for automatically actuating said arm during the travel of the platen, hand controlled means for actuating the first recited shaft to release said second feed roller, and connections between both of said shafts and said sleeve, said connections being fully operative by said hand controlled means but said cam being ineffective on said first recited roller.

3. In a typewriting machine, the combination of a traveling platen, two paper feed rollers arranged side by side, a third feed roller arranged out of line with said first two feed rollers, shafts supporting said feed rollers, connections between said shafts, means connected to one of said shafts to release all of said feed rollers simultaneously, and means operating automatically to release certain only of said feed rollers.

4. In a typewriting machine, the combination of a traveling platen, two paper feed rollers arranged side by side, a third feed roller arranged out of line with said first two feed rollers, shafts supporting said feed rollers, connections between said shafts, means connected to one of said shafts to release all of said feed rollers simultaneously, and means operative by another of said shafts to release two of said feed rollers only.

5. In a typewriting machine, the combination of a platen, terminal feed rollers, an intermediate feed roller, a third feed roller forward of said intermediate feed roller, means for simultaneously releasing all of said feed rollers, and means operative automatically and independently of said terminal feed rollers to release the other two feed rollers.

6. In a typewriting machine, the combination of a platen, terminal feed rollers, an intermediate feed roller, a third feed roller forward of said intermediate feed roller, means for simultaneously releasing all of said feed rollers, and means operative during traveling movements of the carriage to release said intermediate feed roller and said third feed roller while the terminal feed rollers remain in co-operative engagement with the platen.

7. In a typewriting machine, the combination of a hand controlled rock shaft, a sleeve surrounding the same, a connection for turning said sleeve from said rock shaft, a second rock shaft connected to said sleeve, feed rollers supported by said first named rock shaft and by said sleeve, an additional feed roller supported by said second rock shaft, and means effective on said first recited rock shaft to release all of said feed rollers.

8. In a typewriting machine, the combination of a hand controlled rock shaft, a sleeve surrounding the same, a connection for turning said sleeve from said rock shaft, a second rock shaft connected to said sleeve, feed rollers supported by said first named rock shaft and by said sleeve, crank arms on said second rock shaft, a feed roller supported by said crank arms, a deflector supported by said crank arms, and means effective to release all of said feed rollers and also said deflector.

9. In a typewriting machine, the combination of a hand controlled rock shaft, a sleeve surrounding the same, a connection for turning said sleeve from said rock shaft, a second rock shaft, a crank arm thereon, a crank arm on said sleeve, devices connecting said crank arms, paper feed rollers on said rock shafts, and feed roller releasing devices acting on said first recited rock shaft.

10. In a typewriting machine, the combination of a rock shaft, a main feed roller supported thereon, a second rock shaft, a supplemental feed roller supported thereon, connections between said rock shafts comprising a third or intermediate rock shaft provided with crank arms, one connected to the first recited rock shaft and one to the second recited rock shaft, and releasing devices operative on said first recited rock shaft to release both feed rollers.

11. In a typewriting machine, the combination of a main feed roller, a rock shaft 130,

supporting the same, a crank arm on said shaft, a supplemental feed roller, a second rock shaft supporting said supplemental feed roller, a second crank arm on said second shaft, an intermediate rock shaft, a crank arm thereon loosely connected to said first recited crank arm, another crank arm on said intermediate rock shaft and connected by a link with said second crank arm, and 10 releasing means operative on said first recited rock shaft to release both said feed rollers.

12. In a typewriting machine, the combination of a platen; a main feed roller, a 15 supplemental feed roller comprising two sections; and means for controlling said supplemental feed roller comprising a rock shaft, spring pressed crank arms loosely mounted on said rock shaft, and operative 20 crank arms fixed to said rock shaft and loosely connected to said spring pressed crank arms.

13. In a typewriting machine, the combination of a platen; a main feed roller; a 25 supporting shaft therefor; a supplemental feed roller comprising two sections; means for controlling said supplemental feed roller comprising a rock shaft, spring pressed crank arms loosely mounted on said rock shaft, and operative crank arms fixed to 30 said rock shaft and loosely connected to said spring pressed crank arms; connections between said two shafts; and releasing means acting directly on one of said shafts.

35 14. In a typewriting machine, the combination of a platen; a rock shaft; a main feed roller supported thereon; a supplemental feed roller comprising two sections; means for controlling said supplemental feed 40 roller comprising a rock shaft, spring pressed crank arms loosely mounted on said rock shaft, and operative crank arms fixed to said rock shaft and loosely connected to

said spring pressed crank arms; and connections between the rock shaft supporting 45 the main and supplemental feed rollers.

15. In a typewriting machine, the combination of a platen; a rock shaft; a main feed roller supported thereon; a supplemental feed roller comprising two sections; 50 means for controlling said supplemental feed roller comprising a rock shaft, spring pressed crank arms loosely mounted on said rock shaft, and operative crank arms fixed to said rock shaft and loosely connected to 55 said spring pressed crank arms; and connections between the rock shaft supporting the main and supplemental feed rollers, said connections comprising a third rock shaft connected at one end to the supporting 60 rock shaft of the main feed roller, said third rock shaft at its opposite end being connected to the rock shaft supporting the supplemental feed roller.

16. In a typewriting machine, the combination of a platen; a main feed roller; a supplemental feed roller comprising two sections; means for controlling said supplemental feed roller comprising a rock shaft, spring pressed crank arms loosely mounted 70 on said rock shaft, and operative crank arms fixed to said rock shaft and loosely connected to said spring pressed crank arms; and a swinging paper deflector having an opening through which said supplemental roller 75 protrudes, said deflector being supported by said spring pressed crank arms.

Signed at the borough of Manhattan, city of New York, in the county of New York, and State of New York, this 23rd day of 80 May, A. D. 1921.

JOSEPH PHELPS.
